UNITED STATES PATENT OFFICE.

BLANCHE CERVELLI, OF SAN FRANCISCO, CALIFORNIA.

REDUCING BRASSIÈRE.

Application filed October 5, 1922. Serial No. 592,536.

To all whom it may concern:

Be it known that I, BLANCHE CERVELLI, a citizen of the United States, and a resident of San Francisco, in the county of San Francisco and State of California, have invented certain new and useful Improvements in Reducing Brassières, of which the following is a specification.

The present invention relates to reducing 10 garments and is made especially for women who are fleshy over the bust and shoulders directly behind, and also in front of the arms. It is the object of this invention to reduce this excess flesh which is objectionable when in evening dress because of the overhanging of superfluous flesh and its resulting appearance which is embarrassing.

It is a further object of this invention to provide a garment which induces copious 20 perspiration, thereby causing a loss of excess flesh to the wearer without any harmful effect on the health.

Further, it is an object of this invention to provide a reducing garment which may be 25 easily adjusted to position upon the wearer.

Also, it is an object of this invention to provide a reducing brassière which may be worn under an evening gown.

It is an object of this invention to provide 30 a reducing brassière which may be worn while engaging in all forms of athletics and allow the freedom of movement necessary.

These and other objects which might hereinafter appear are attained in the manner 35 made apparent by the foregoing description and the accompanying drawings forming a part thereof and in which:

Fig. 1 is a rear perspective view.

Fig. 2 is a front perspective view.

Fig. 3 is a development of the brassière 40 showing the closure means and also how the upper extensions may be folded in so that the garment may be worn as a bandeau underneath an evening gown.

Similar letters of reference indicate corresponding parts throughout the figures.

Referring to the drawing, 1 represents the body of the brassière and is made of sheet rubber; 2 and 4 are substantially triangular shaped extensions of the same material 50 which are connected by the armpit portions 3; 5 represents the shoulder straps which are made of elastic to allow perfect freedom of the arms of the wearer. The body 1 of 55 the brassière is hereinafter termed the bust

encircling member and in use extends entirely around and completely covers and encircles the body of the wearer in the region of the bust as shown in the drawings.

The brassière is constructed of one continuous sheet of rubber without any opening at the front. The purpose of this is to press the soft flesh of the front of the body toward the rear thus giving a smooth flat front. The rear edges are provided 60 with the lacing 8 and also the hooks 6 and cooperating eyes 7. In adjusting the garment on the wearer, the laces are loosened and then the brassière placed upon the body with the opening 11 in front. The edges 65 9 and 10 are next connected by means of the hooks and eyes 6 and 7, whereupon the garment is turned around on the wearer so, that the opening 11 is in its normal position at the rear. The wearer now slips her 70 arms through the arm holes 12, and adjusts the garment to snugly confine the body, by means of the laces 8. Obviously the lace adjustment may be made before the brassière is put on, but only in the case 75 80 when the wearer is able to reach the hooks and eyes at the rear. Also the laces 8 may be omitted and the hooks and eyes or any other suitable closure means used.

Thus it will be seen that a reducing garment is provided which causes the wearer to perspire copiously by virtue of the fact that the garment snugly fits the parts to be reduced and prevents contact with the air. Viewing Figures 1 and 2 it will be seen 90 that the extensions 4 and 5 are so shaped as to allow the garment to be worn underneath a low cut waist without being visible and yet said extensions act to reduce the soft flesh about the shoulders and arms of 95 corpulent women. Also by virtue of this particular arrangement of extension the bust of the wearer is not pushed upward to give the appearance of a high bust, but rather is confined at the sides, thus giving a flat 100 appearance at the front and also at the back. The portions 3 which come at the armpit act as dress shields and the use of separate shields in connection with this brassière is not necessary.

This garment is particularly adapted for use by singers and women engaging in athletics because the elasticity readily permits of deep breathing as well as freedom of movement. Because of its simplicity of 110

structure it may be brought on the market at a price considerably lower than that of similar garments.

While I have shown and described one form of brassière, it will be apparent that in view of this disclosure there may be provided other forms or modifications and it is to be understood that the disclosure is intended as being illustrative of my invention and certain departures may be made without departing from the spirit of the invention, and it is to be understood that I do not intend to be limited to any specific or particular embodiment of the invention except as defined in the claim.

Having thus described my invention, what I claim and desire to secure by Letters Patent of the United States is:

A reducing brassière comprising a bust encircling member of elastic non-ventilative material extending entirely around and completely covering and encircling the body of the wearer in the region of the bust, and an upwardly tapering flesh reducing ex-

tension of elastic non-ventilating material 25 at each side of the front and back of the bust encircling member and extending above the regions of the arm pit, each flesh reducing extension being of substantially triangular form and having its wide lower 30 portion connected to the bust encircling member, arm pit portions connecting the front and back extensions at each side, the upper portion of the front and back extensions at each side also being connected, the 35 flesh reducing extensions being designed to confine the flesh about the arms of the upper portions of the back and chest, the adjacent edges of the extensions at the front and the adjacent edges of the extensions at the 40 back diverging from each other toward the upper portions of the extensions so as to leave the central upper portions of the back and chest exposed to enable the garment to be worn with evening or dress clothes. 45

In testimony whereof, I hereunto affix my signature.

BLANCHE CERVELLI.
